(57) **CLAIM**

The ornamental design for a microwell plate assembly, as shown and described.

DESCRIPTION

FIG. 1 is a top perspective view of the first embodiment of a microwell plate assembly.

FIG. 2 is a bottom perspective view of the microwell plate.

FIG. 3 is a top view of the microwell plate assembly.

FIG. 4 is a bottom view of the microwell plate assembly.

FIG. 5 is a front view of the microwell plate assembly.

FIG. 6 is a back view of the microwell plate assembly.

FIG. 7 is a side view of the microwell plate assembly.

FIG. 8 is an opposite side view of the microwell plate assembly.

FIG. 9 is a top view of the microwell plate assembly;

FIG. 10 is a cross sectional view of the microwell plate assembly taken along line 10-10 of FIG. 9.

FIG. 11 is a cross sectional view of the microwell plate assembly taken along line 11-11 of FIG. 9.

FIG. 12 is a top perspective view of the second embodiment of a microwell plate assembly.

FIG. 13 is a bottom perspective view of the microwell plate assembly of FIG. 12.

FIG. 14 is a top view of the microwell plate assembly of FIG. 12.

FIG. 15 is a bottom view of the microwell plate assembly of FIG. 12.

FIG. 16 is a front view of the microwell plate assembly of FIG. 12.

FIG. 17 is a back view of the microwell plate assembly of FIG. 12.

FIG. 18 is a side view of the microwell plate assembly of FIG. 12.

FIG. 19 is an opposite side view of the microwell plate assembly of FIG. 12.

FIG. 20 is a top view of the microwell plate assembly;

FIG. 21 is a cross sectional view of the microwell plate assembly of FIG. 12 taken along line 21-21 of FIG. 20; and,

FIG. 22 is a cross sectional view of the microwell plate assembly of FIG. 12 taken along line 22-22 of FIG. 20.

(Continued)

The broken lines depict portions of the microwell plate assembly that form no part of the claimed design.
